INDICATING UNIT

Charles G. Sims, Fox Point, Wis., assignor to Cutler, Hammer, Inc., Milwaukee, Wis., a corporation of Delaware

Filed Mar. 30, 1959, Ser. No. 55,247

Term of patent 14 years

(Cl. D26—13)

Fig. 1

Fig. 3

Fig. 2

FIGURE 1 is an isometric view of an indicating unit incorporating my new design;

FIG. 2 is a side elevational view to reduced scale of the indicating unit shown in FIG. 1, the opposite side being a mirror image of that shown;

FIG. 3 is an end elevational view to reduced scale of the indicating unit shown in FIG. 1, the opposite end being a mirror image of that shown.

The dominant features of my design are shown in solid lines. Broken line showings of possible legible matter are for illustrative purposes only. The bottom or back side, not shown, of my design is conventional. A portion of the drawing is diagonally lined to illustrate transparency.

I claim:

The ornamental design for an indicating unit, substantially as shown and described.
